CLAIM

The ornamental design for a charger for smart ring, as shown and described.

DESCRIPTION

FIG. 1 is a top perspective view of a first embodiment of a charger for smart ring showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a bottom perspective view thereof;

FIG. 9 is another top perspective view of the charger for smart ring in an open position;

FIG. 10 is a top perspective view of a second embodiment of a charger for smart ring showing our new design;

FIG. 11 is a front view thereof;

FIG. 12 is a rear view thereof;

FIG. 13 is a left-side view thereof;

FIG. 14 is a right-side view thereof;

FIG. 15 is a top view thereof;

FIG. 16 is a bottom view thereof;

FIG. 17 is a bottom perspective view thereof; and,

FIG. 18 is another top perspective view of the charger for smart ring in an open position.

The broken lines in the figures depict portions of a charger for smart ring that form no part of the claimed design.
